UNITED STATES PATENT OFFICE.

HOWARD H. BAKER, OF BUFFALO, NEW YORK, ASSIGNOR TO UNITED STATES FUSE CORPORATION, OF BUFFALO, NEW YORK, A CORPORATION OF NEW YORK.

FUSE.

1,406,434.

Specification of Letters Patent. Patented Feb. 14, 1922.

Application filed November 15, 1918. Serial No. 262,720.

To all whom it may concern:

Be it known that I, HOWARD H. BAKER, a citizen of the United States, residing at Buffalo, in the county of Erie and State of New York, have invented new and useful Improvements in Fuses, of which the following is a specification.

This invention relates to a refillable fuse and has for its object the production of such a fuse which can be manufactured at comparatively low cost, which can be readily dismembered and assembled for the purpose of replacing a blown out fuse-link, which permits of quickly coupling the fuse-link with the terminals so as to guard against any looseness of parts which might produce an imperfect contact or arcing, which is so designed as to practically prevent shocking a person who is handling the fuse, and which is improved in other respects so as to render the fuse as a whole more durable and not liable to get out of order.

In the accompanying drawings:

Figure 1 is a longitudinal section showing one embodiment of my invention. Figure 2 is a side elevation of the same with the cover removed and the catches for holding the cover in section. Figures 3 and 4 are cross sections taken on the correspondingly-numbered lines in Fig. 2. Figure 5 is a group of perspective views of the several parts of the fuse in a dismembered condition. Figure 6 is a fragmentary longitudinal section of the fuse showing a modified form of the coupling clip for detachably connecting the fuse-link with one of the terminals. Figure 7 is a perspective view of the form of coupling clip shown in Fig. 6.

Similar characters of reference indicate corresponding parts throughout the several views.

In its general organization, this fuse comprises a hollow enclosing box or casing, two terminals mounted on opposite ends of this box so that the outer ends of the same project beyond opposite ends of the box for connection with the terminals of the fuse block while their inner ends are arranged within the box, and means for detachably connecting a fuse link within the box to the inner ends of the terminal.

Although these terminals may be variously constructed, the same are preferably made in the form of flat bars 1 which are constructed of any suitable conducting ma-

terial, such as copper, which is of uniform thickness throughout its length. The box or enclosing casing is constructed of electric insulating material such as bakelite, and comprises a body 2 and a cover 3. The body is composed of an outer longitudinal wall 4, an inwardly-projecting flange 5 arranged at one of the longitudinal edges of this wall, and two transverse flanges 6, 6, projecting inwardly from opposite ends of said wall, these several members of the body being preferably constructed integrally in any suitable manner from insulating material. The cover is composed of an outer longitudinal wall 7, a comparatively wide flange 9 projecting inwardly from one of the longitudinal edges of this wall, a comparatively narrow flange 8 projecting inwardly from the other longitudinal edge of this wall, and two transverse flanges 10, 10, projecting inwardly from opposite ends of this wall, the several members of this cover being also preferably formed integrally of suitable insulating material in any suitable manner. In the assembled position of the body and cover of the box the inner edge of the narrow longitudinal flange of the cover engages with the inner edge of the longitudinal flange on the body, the wide longitudinal flange of the cover engages with the unflanged longitudinal edge of the body and the corresponding transverse flanges of the cover and body engage with each other, thereby forming the hollow box or enclosing casing. It will be noted that by thus constructing the sections of the box or casing in this manner, the same are of non-symmetrical form in cross section and the joints between opposite longitudinal sides thereof are out of line with each other transversely of the box, so that it is impossible to assemble the body and cover in any other way excepting the correct way and thereby facilitating this assemblage and enabling the cover to be quickly and definitely engaged at its opposite ends with the catches or retaining devices which are arranged on opposite ends of the body and are of different constructions as will be hereinafter fully described.

In order to center or align the cover and body relatively to each other when assembling them, and cause their outer surfaces to be held flush with each other, centering or aligning means are employed which in the

preferred construction shown in the drawings, consist in providing the inner edge of the wide flange and the adjacent parts of the transverse flanges of the cover with an inclined or beveled face 11 which engages with a correspondingly inclined face or seat 12 on the inner side of the unflanged edge of the body-wall and the adjacent parts of the transverse flanges thereof, and the inner edge of the narrow longitudinal flange of the cover and the adjacent parts of its transverse flanges is provided with an inclined or beveled face 13 which engages with a correspondingly inclined or beveled face 14 on the inner edge of the longitudinal flange of the body and the adjacent parts of the transverse flanges of the latter, as shown in Figs. 2-5. Longitudinal displacement of the body and cover forming the two box sections is prevented and holding the opposite ends of the body and cover flush or in alignment is accomplished by providing the longitudinal flange of the body adjacent to the inner side of the central part of its beveled face with a notch or recess 15 and arranging a tongue or projection 16 on the narrow longitudinal flange of the cover adjacent to the inner side of the central part of the beveled face thereon and engaging the same with said recess, thereby causing the cover and body when assembled to be securely and reliably held against displacement relatively to each other both lengthwise and crosswise and insuring the proper operation of the parts which are mounted on the body and co-operate with the cover.

The corresponding pair of transverse flanges at the same ends of the body and cover of the box in effect form a head on this end of the enclosure and the opposing surfaces of these flanges on the body and cover are provided with notches or recesses 17, 18, which in the assembled position of the cover and body together form an opening or slot in which the central part of one of the terminals is arranged so that the inner end of this terminal is arranged within the box and the outer end externally thereof. These terminals may be secured to the body of the box in any suitable manner, but as shown in Figs. 2, 3 and 4, each of these terminals is preferably secured to one of the transverse flanges of the body by means of screws 20 passing through openings in the central part of the terminal and engaging their heads with one side of the terminal while the threaded shanks of the screws engage with threaded sockets or sleeves 19 which are mounted in the respective transverse flange of the body and the adjacent part of the side wall thereof. These threaded sockets are preferably constructed of metal and embedded in the body by molding or casting the latter around these sockets during the manufacture of the

same. In order to prevent these sockets from turning circumferentially, the peripheral surfaces of the same are made of irregular form, for instance, hexagonal, as shown in Fig. 5, thereby interlocking the sockets circumferentially with the body. Each of these sockets is also provided with a recess 21 in its periphery which preferably has the form of an annular groove into which the adjacent part of the molded body enters in the form of a key, thereby positively anchoring or interlocking the socket with the body and preventing the same from being pulled out when the screw which enters the same is tightened for clamping the terminal against the respective end of the body.

Various means may be employed for detachably connecting opposite ends of the cover with the corresponding ends of the body, but those which are shown in the drawings have been found satisfactory in practice and are therefore preferred. As there shown, a catch is mounted on each end of the body for detachably engaging with the corresponding end of the cover. Each of these catches comprises an outer transverse plate 23 which engages the outer ends of the body and cover and extends across the joint between the same and is provided with a slot 24 which receives the adjacent part of the respective terminal, a locking lip 25 projecting inwardly from the front end of this plate and engaging with an outwardly-facing shoulder formed on the outer side of the adjacent end of the cover by producing a notch 27 in the latter, an inner plate 29 arranged between the inner side of the rear part of said outer plate and the adjacent transverse flange of the body, this inner plate being connected at its rear end with the rear end of the outer plate while its front edge terminates in rear of the slot 24 in the latter, and a longitudinal attaching flange 28 extending longitudinally inward from the front edge of the inner plate and secured between the rear side of the central part of the adjacent terminal and the front side of the adjacent transverse flange of the body by means of the screws 20 which pass through openings 30 in this flange. Each of these catches is preferably constructed integrally of sheet metal although the same may be otherwise constructed, if desired. One of the lips 25, for instance the one shown at the upper end of Fig. 1, forms a plain hook while the other which is shown at the lower end of Fig. 1, is provided at its inner or free end with a laterally projecting inclined flange 31 which permits of manipulating this catch for disengaging the same from the cover when dismembering the parts. When assembling the cover and body, one end of the cover is first engaged with the plain lip 25 and then

the opposite end of the cover is pressed against the inclined flange 31 of the other lip 25, whereby the latter will be sprung away from the body and cover sufficiently 5 to permit the cover to pass the flanged lip, and when the cover has been fully seated against the body, then the flanged lip will automatically spring back into engagement with the respective outer shoulder 26 of the 10 cover and retain the same in place. The outer sides of the transverse flanges of the body and cover of the box are preferably recessed, as shown at 32, for receiving the adjacent parts of the plates of the catches, 15 and the notches 27 in the cover are sufficiently deep to receive the plain and flanged lips 25, whereby the parts of the catches are retained within the surface dimensions of the body and cover, thereby avoiding any 20 projection or obstruction on the exterior of the box or casing which might interfere with the proper manipulation of the fuse and its application to or removal from the fuse block or switch board with which the same 25 is intended to co-operate.

Although the fuse link which may be employed in connection with this fuse may be of different forms, and still accomplish its purpose, the same is preferably constructed 30 of a strip of fusible metal so as to form two comparatively wide and flat end tabs 33, 33, a central section 34 of comparatively large area, and two comparatively narrow filaments 35 connecting opposite sides of the 35 central section with the end tabs, as shown in Fig. 5. By this means two blow-out spots or fusing regions are formed on the fuse link by the filaments which renders the fuse more sensitive and increases the protection 40 for the apparatus with which this fuse is associated.

While a variety of means may be employed for connecting the opposite ends of the fuse link with the inner ends of the terminals, those which are shown in the drawings are preferred and constructed as follows:

36, 36 represent coupling pins projecting laterally from the inner ends of the terminals through openings 37 in the end tabs of the fuse link so that the latter engages on one side with one side of the terminals. Each end of the fuse link is firmly clamped against the respective terminal so as to hold the 55 same reliably in engagement therewith and produce a good electric contact by means of a coupling clip which is of substantially U-shaped form and provided with a front rigid jaw 38 engaging with the front side of the 60 fuse link, a rear resilient jaw 39 engaging with the rear side of the adjacent terminal, and a transverse web 40 connecting the outer ends of these jaws. The front jaw of this coupling clip is preferably made flat so as 65 to produce a contact of large area with the

fuse link and the rear jaw is preferably constructed of S-shaped form so that upon slipping this coupling clip over the fuse link and the respective terminal, a resilient wedging engagement of the rear jaw will be exerted against the terminal which operates to hold the fuse link and terminal reliably in engagement over a wide area of contact and thus insure a good electrical connection between the same. In order to further increase the electrical contact between the fuse link and the clip, the end portions or tabs of the link are roughened, as shown at 41, so that when the front dog or clip engages with the same, minute furrows or grooves are 70 formed or cut in the link which additionally operate to insure a perfectly clean contact between the same. When the coupling clips are applied to the link and terminals, the webs of the clips are arranged so close to the 75 adjacent wide longitudinal flange of the cover that the latter forms a stop and prevents the clips, in the assembled position of the parts, from moving laterally out of engagement with the fuse link and terminals, 80 so that accidental disconnection of the fuse link from the terminals is rendered impossible. Longitudinal displacement of the clips relative to the fuse link and terminals may be prevented in numerous ways, for 85 instance, as shown in Figs. 1, 2, 4 and 5, this is accomplished by providing the front jaw of each clip with a slot 42 extending inwardly from its free end and engaging this slot with the coupling pin 36 on a terminal, 90 but if desired, this slot in the front jaw 43 of the clip may be omitted, as shown in Figs. 6 and 7, in which case longitudinal displacement of the clip relative to the terminal and fuse link may be prevented by engaging this clip with the terminal and 95 fuse link between the coupling pin 36 and the adjacent transverse flanges of the body and cover of the box, as shown in Fig. 6.

In order to render possible easy removal 100 of the clips from the link and terminals, either by means of the fingers or by means of a tool, a rib or shoulder 44 is formed externally on each clip at the corner or junction between the front jaw and the web, as shown 110 in Figs. 1, 4, 5, 6 and 7.

When the cover of this box is removed, the internal parts of the fuse are fully exposed to view and ample room is afforded for conveniently and efficiently applying a fuse-link to the terminals or replacing the same by a new one when blown out. Furthermore, the enclosure which is thus produced for the fuse link and associated parts, is practically air tight so that the same is unaffected by 120 moisture and is also not liable to injure anything adjacent to the fuse link when it burns out. Moreover, the amount of metal which is exposed on the exterior of the box is reduced to a minimum which is a great ad- 125 130

vantage inasmuch as it reduces to a minimum the liability of injuring an operator by shocks when manipulating the fuse in quarters which are dark or poorly lighted.

5. I claim as my invention:

1. A fuse comprising a box having a body and a cover, terminals mounted at opposite ends of the box, and means for detachably connecting opposite ends of the body and cover, comprising catches each of which has an outer plate mounted on the body and provided with a lip engaging with the cover and with a slot which receives the adjacent terminal.
10. 2. A fuse comprising a box having a body and a cover, terminals mounted at opposite ends of the box, and means for detachably connecting opposite ends of the body and cover, comprising catches each of which has an outer plate provided with an opening receiving the adjacent terminal, a lip at the front end of said outer plate engaging with said cover, an inner plate connected at its rear end with the corresponding end of the outer plate, and an inwardly projecting flange secured to the body.
15. 3. A fuse comprising a box having a body and a cover, terminals mounted at opposite ends of the box, and means for detachably connecting opposite ends of the body and cover, comprising catches each of which has an outer plate provided with an opening receiving the adjacent terminal, a lip at the front end of said outer plate engaging with said cover, an inner plate connected at its rear end with the corresponding end of the outer plate, and an inwardly projecting flange secured to the body, the outer ends of said body and cover being recessed to receive said
20. 40. 4. A fuse comprising a box, terminals mounted on the box and provided with pins, a fuse link having openings which receive said pins, and means for clamping said link upon said terminals comprising U-shaped coupling clips each of which forms two jaws
